UNITED STATES PATENT OFFICE.

RALPH BERNARD STIERT, OF SAPULPA, OKLAHOMA.

HEADLIGHT FOR MOTOR VEHICLES.

Application filed March 14, 1925. Serial No. 15,644.

My invention relates to improvements in headlights for motor vehicles, and it consists in the combinations, constructions, and arrangements herein described and claimed.

5 An object of my invention is to provide headlights of the character described in which two sources of light and two reflectors are employed in each unit one above the other and each focused upon different portions of the road ahead of the vehicle upon which the headlights are mounted.

10 A further object of my invention is to provide headlights of the character described by means of which light may be projected at a distance ahead of the vehicle or immediately in front of the vehicle upon which the headlights are mounted, and therefore adaptable to both city and country driving.

15 20 A further object of my invention is to provide a device of the character described which is durable in construction and which is thoroughly practical for the purpose intended.

25 Other objects and advantages will appear in the following specification, and the novel features of the invention will be particularly pointed out in the appended claim.

30 My invention is illustrated in the accompanying drawings, forming part of this application, in which—

Figure 1 is a front elevation of an embodiment of my invention,

35 Figure 2 is a side elevation of the device shown in Figure 1,

Figure 3 is an enlarged sectional view along the line 3—3 of Figure 1, and

Figure 4 is a sectional view along the line 4—4 of Figure 2.

40 In carrying out my invention I make use of an elongated casing 1 having curved top and bottom walls. A pair of reflectors 2 and 3 are mounted one above the other within the casing 1. The curvature of the top and bottom walls of the casing is substantially that of the curvature of the adjacent edges of the reflectors 2 and 3 which are circular. The reflector 2 is parabolic in cross section. This reflector has the property of projecting light as from an incandescent electric lamp bulb 4 disposed therein to a point some distance ahead of the casing 1 in parallel rays. The reflector 3 is shallow and has the properties of projecting light as from an incandescent bulb 5 disposed there-

in to a point near the casing 1 in diverging rays.

Each of the incandescent bulbs 4 and 5 are mounted in suitable sockets 6 which are connected by means of conductor wires 7 to a current source such as the storage battery with which the motor vehicle is usually equipped. Suitable switches, not shown, are employed for operating the lamps 4 and 5 selectively and simultaneously at will.

80 A glass lens 8 is disposed at the front of the casing 1 and in front of the reflectors 2 and 3 and secured against movement relative thereto. The glass 8 is provided with vertical flutings 9 for causing slight diffusion of rays of light reflected from the reflectors 2 and 3 and from the lamps 4 and 5, respectively. It should be understood that while I have shown and described a lens 8 with vertical flutings that any type of lens glass for properly distributing light so as not to produce a glare to drivers of vehicles approaching the vehicle equipped with my headlights may be used to equal advantage.

85 Means for further assisting in projecting the rays from the lamps 4 and 5 respectively to the relative positions and distances from the vehicle described and for stopping a projection of stray light rays is provided in a hood 10 which is hingedly mounted at 11 to the casing 1 at the top. This hood 10, as reference to Figure 1 will indicate, has substantially the same contour at that point adjacent the casing as the casing, and adjacent to its outermost ends 12 has a substantially rectangular cross sectional contour.

90 95 The end 12 of the hood is inclined as shown in Figure 2 so that the upper wall overhangs the lower wall by several inches.

A plain clear glass 13 is mounted in the outer end 12 of the hood so as to exclude dust, mud and the like from the interior of the hood.

100 105 The hood 10 has a substantially horizontal partition wall 14 extending longitudinally therethrough which serves to separate the rays of light from the lamp 4 from those of the lamp 5 and vice versa.

110 It will be noted from a close inspection of Figures 1 and 2 that the hood 10 has the appearance of inclining downwardly as it approaches the outer end 12. This is due to the fact that the cross sectional contour at

the outer end is substantially rectangular while at the innermost is that shown in Figure 4, the rounded top and bottom walls being gradually diminished as the outer end is 5 approached.

The entire inner wall of the hood 10 with the exception of those portions between the letters $x-x$ and $y-y$ is provided with a coating of material for reflecting light such 10 as nickel or silver plate. The portions confined between the letters $x-x$ and $y-y$ are dull and are not intended to serve as reflecting surfaces.

The hood 10 is secured against movement 15 relative to the casing 1 by the provision of a bolt 15 which is projected through a lug 16 carried by the casing 1 and into the hood 10.

The hood 10 is fashioned to partially receive 20 the outermost end of the casing 1, as shown at 17, thereby preventing the admission of moisture and the like to the interior of the hood.

From the foregoing description of the 25 various parts of the device, the operations thereof may be readily understood. My improved headlight for motor vehicles is intended for use in pairs in precisely the same position on the vehicle as the ordinary type 30 of headlight, and with a suitable electric current source and circuit including switches for controlling and operating the lamps 4 and 5 separately.

When the lamp 4 alone is illuminated, 35 light therefrom is transmitted and projected from the reflector 2 through the lens glass 8 in substantially parallel rays to a point greater than fifty feet (in the present embodiment of the invention) in front of the 40 vehicle, and for a long distance ahead upon the road so that the driver may see the road clearly a long distance in front of the vehicle.

The upper portion of the hood 10 above 45 the partition 14 serves to confine and prevent the transmission of stray rays of light in any other direction than that just described.

The lamp 4 is normally used when driving 50 in the open country and where motor vehicles are not approaching from the opposite direction, and where it is very essential that the road be brightly illuminated for some distance ahead, since usually driving 55 under such conditions permits greater speed of the vehicle.

Let us assume however that a vehicle is

approaching from the opposite direction, and that the vehicle is upon a rural road 60 out of the city limits. The light from the lamp 4 will not blind the driver of the approaching vehicle, because of the peculiar construction of the hood 10 which prevents the projection of rays to a point above or on a level with the driver's seat in the approaching vehicle. It is well to note at this point that ordinary headlights focused at a distance in front of the vehicle must be dimmed upon the approach of a vehicle in an opposite direction so as not to endanger 70 the safe approach of the approaching vehicle. Thus both the lamps 4 and 5 may be kept in continuous illumination for rural driving, thus saving the driver of the vehicle from continually turning on and off his 75 long distance lamps, which is particularly tiresome upon long journeys.

It is readily apparent that the inclination of the shaft of light from the lamp 5 is so sharp as to preclude all possibility 80 of blinding the driver of the approaching vehicle.

It should be noted, of course, that the lamp 5 may be kept in operation all the time that the vehicle is in use and always for city 85 driving where the lamp 5 alone is employed, since traffic in large cities is so great that the use of a long distance headlight which must necessarily project a shaft of light above the cowl of the approaching vehicle 90 at some point therealong is prohibited and usually expressly prohibited by ordinance.

I claim:

A headlight comprising a casing, a reflector mounted in said casing, a second reflector mounted in said casing, a hood carried by said casing and confining the projected rays of light from the reflectors to a predetermined area, a partition disposed in said hood and being positioned between the reflectors, a diffusing lens disposed in front of said reflectors, whereby the rays from said reflectors will be diffused by said lens, thus causing the rays to be reflected and re-reflected by the inner walls of said hood and outer walls of said partition, and a glass disposed at the open end of said hood for protecting the interior of said hood from foreign matter, said glass and the walls of said hood and partition being inclined at a predetermined angle for directing the rays of light of each reflector upon predetermined portions of the road in front of the vehicle.

RALPH BERNARD STIERT.
